UNITED STATES PATENT OFFICE.

HARRY J. KEATING, OF CHICAGO, ILLINOIS.

ADVERTISING DEVICE.

1,084,641.

Specification of Letters Patent. Patented Jan. 20, 1914.

Application filed August 6, 1912. Serial No. 713,685.

To all whom it may concern:

Be it known that I, HARRY J. KEATING, a citizen of the United States, residing at Chicago, in the county of Cook and State 5 of Illinois, have invented a certain new and useful Improvement in Advertising Devices, of which the following is a full, clear, concise, and exact description, reference being had to the accompanying drawings, 10 forming a part of this specification.

My invention relates to advertising devices and has for its specific object the provision of a movable sign or advertisement.

The device in the form herein shown 15 templates preferably a character illustration which may be periodically changed so as to occupy different positions, and which at the same time has provision for the display, one after another of a plurality of 20 cards of advertising matter.

The invention herein concerns itself particularly with the operating mechanism to direct a structure of this character, and while the same is herein set forth in connection 25 with a device as above outlined, my invention is not to be so limited as it may be used in sundry ways without departing from its spirit, and the invention is of course likewise capable of various modifications 30 as will be readily understood by those skilled in the art. I will describe however specifically one form which my invention may take by referring to the accompanying drawing, in which—

35 Figure 1 is a front view of a device adapted to be operated in accordance with my invention; Fig. 2 is a rear view thereof showing the operating mechanism, and Fig. 3 is a detail view of the operating mechanism.

40 Referring specifically to Fig. 1, I set forth an advertising device which may take the form of a man 1 who has a movable arm 2, in this instance designed to oscillate, the arm as here shown carrying a safety 45 razor. The lower portion of the device has a preferably circular aperture 3 through which is displayed certain advertising matter periodically changed after a number of 50 oscillations of the arm 2.

55 Referring more particularly to Fig. 2, I show the arm 2 as being fastened to a pivotally mounted strip 3, said strip being pivotally mounted at 4 to a bracket 5 permanently secured to an upright 6, to which up-

right the illustration is likewise preferably attached. The bracket 5 also carries a spring 7. The arrangement of the arm is such that it is overweighted, thereby tending to occupy the position shown in Fig. 2. A plunger 8 controlled by a solenoid 9 as will presently appear periodically draws the left hand extremity of the strip 3 downwardly, whereafter the energization of the solenoid 9 is discontinued and the overweighted arm 2 returns toward the position shown in Fig. 2, striking against the spring 7 and thereby being rotated again in a contra-clockwise direction, Fig. 2, to assist the action of the solenoid 9. The core 8 is connected by 70 means of a rod 10 with the strip 3. The core 8 likewise carries a circuit controlling arm 11 and a cam 12. A contact 13 is mounted on the outside of the solenoid and is connected by means of a conductor 14 with one terminal 15 of the solenoid and the other terminal 16 of the solenoid is connected by means of a conductor 17 preferably with a lamp 18, which lamp 18 is then connected by means of a conductor 19 with a generator 20, the other terminal of said generator or source of current supply being connected by means of a conductor 21 with a contact spring 22 insulatingly mounted on the solenoid structure. This contact 75 spring has a downwardly extending arm 23 adapted periodically to be engaged by the roller 24 carried by the arm 11. The spring 22 normally engages the contact 13 when the device is in the position shown in 80 Fig. 3, thereby closing circuit through the solenoid to attract the core 8 until such time as the cam 12 enters between the spring 22 and its mounting plate 25 and pushes the 85 said spring away from the contact 13. At 90 this time the roller 24 is lower than the lowermost extremity of the arm 23. As the circuit through the solenoid is broken, the overweighted arm 2 tends to return to its normal position and thereby withdraws the 95 core 8 from within the solenoid, the roller 24 at the same time engaging the righthand side of the arm 23 to maintain the spring 22 away from the contact 13 until this roller 24 has been carried upwardly to a point 100 higher than the top of the spring 22, at which time the strip 3 has engaged the spring 7 and is normally rotated in the opposite direction to assist the solenoid 9 whose circuit has been again closed by the 105

110

release of the spring 22 from the roller 24 to again attract the core and carry the arm 2 in a contra-clockwise direction (Fig. 2).

A plug 26 is preferably provided so that 5 the device may be attached to any lamp circuit, which lamp or power circuit is diagrammatically indicated by the generator 20 in Fig. 3. The rod 10 also carries a bracket 27 which has a pawl 28 coöperating 10 with a ratchet wheel 29 to move this ratchet wheel one step for every complete movement of the arm 2. A holding pawl 30 maintains the ratchet in its operated position. The ratchet is fixedly secured to a cam 31 15 which moves an arm 32 toward the right once for every complete revolution of the ratchet wheel 29. This arm 32 has a pivoted pawl 33 adapted to engage a star wheel 34 to move it to an angle of ninety degrees 20 for every actuation of the arm 32. It will thus be seen that depending upon the number of teeth in the ratchet wheel 29 the star wheel 34 is rotated a predetermined angular distance once in the course of any predetermined number of actuations of the arm 2. 25 The star wheel 34 is connected with a disk 35 having a plurality of advertising signs thereon which are adapted, one after another to be displayed through the opening 3, the disk 35 showing in dotted lines at 36 the outline of such advertising matter.

From what has been described it will be seen that I have provided a very simple mechanism to control the oscillatory movement of the arm 2 and at the same time to 35 control the periodic change of advertising matter. The broad feature of my invention will be thus understood and

What I therefore claim as new and desire to secure by Letters Patent is: 40

Apparatus of the character described comprising a movable element, a solenoid having a core to periodically actuate said element, said element being overweighted to automatically return to its normal position 45 when released from the influence of said solenoid, and means controlled by said core to control the circuit through said solenoid, said last aforesaid means comprising a contact spring a contact, a cam carried by said 50 core to break the circuit between said spring and said contact, when said core is in its limiting position, and means to continue the interruption of said circuit until the said core has been moved to its other limiting position. 55

In witness whereof, I hereunto subscribe my name this 22nd day of July, A. D., 1912.

HARRY J. KEATING.
